UNITED STATES PATENT OFFICE.

EBENEZER EMMET REID, OF BALTIMORE, MARYLAND, ASSIGNOR TO HERCULES POWDER COMPANY, OF WILMINGTON, DELAWARE, A CORPORATION OF DELAWARE.

PROCESS OF RECOVERING TERPENE PRODUCTS FROM GASOLINE-TERPENE MIXTURES.

No Drawing.

Application filed August 9, 1927. Serial No. 211,859.

In the manufacture of turpentine, pine oil and rosin by the steam and solvent process, the oil of turpentine is steamed out of the chips, and the rosin is extracted from the 5 turpentine-free chips by means of a light hydrocarbon, usually a low boiling gasoline. From the solution or mixture thus obtained the gasoline is separated by distillation, leaving the rosin as a residue. The gasoline is not, 10 however, recovered in a pure state, but the distillate comprises a mixture of gasoline with terpenes, terpene alcohols, etc., from which the gasoline cannot be separated by fractional distillation because its boiling 15 range overlaps that of the terpene compounds. The capacity of the mixture for re-use is limited, and the commercial value of the terpene products and gasoline, if separated, is substantially greater than the commercial 20 value of the mixture.

The object of the invention is to effect a separation, to a substantial degree, from the gasoline of the terpene products, so that they may be obtained in a relatively pure 25 state, thereby enabling, also, the gasoline to be frequently re-used.

This object I have accomplished by a process of extraction with sulfur dioxid, one specific example of which will now be described.

30 400 parts by volume of gasoline containing terpenes, terpene alcohols, etc., are mixed, preferably with agitation, with an equal volume of liquid sulfur dioxid cooled to (say) -20° C., whereupon two layers form. The 35 upper layer (A), comprising 270 parts partially purified gasoline, is readily separated from the lower layer (B) comprising chiefly or wholly terpene compounds in solution in liquid sulfur dioxid.

40 The upper layer (A) may be then treated in the same way with 270 parts of liquid sulfur dioxid and separated into an upper layer (C), comprising 175 parts gasoline, and a lower layer (D) comprising 65 parts comprising chiefly or wholly terpene compounds in solution in liquid sulfur dioxid.

45 That little, if any, gasoline remains in lower layers B and D is demonstrated by the fact that if layer B is subjected to the sulfur dioxid treatment described, no separation results.

50 Careful determination of percentages of polymerization residue and of specific gravities shows that the portions of the original 55 mixture which were supposedly inseparable

and which were soluble in the liquid sulfur dioxid possess substantially higher densities and lower unpolymerized values than the original material, which in turn possesses substantially higher density and lower unpolymerized value than layer C, showing that there was substantial concentration of the terpenes in the sulfur dioxid.

When practicing the process on a small scale, the sulfur dioxid may be allowed to distil off from the SO₂-terpene solution at room temperature and the recovered terpene products subsequently washed with dilute alkali. In practicing the process on a commercial scale, it is preferred to carry out the process 70 in a closed vessel to prevent loss by escape of volatilized sulfur dioxid, the latter being separated by volatilization into receivers from which it is again liquefied for re-use.

The specific process described is merely 75 illustrative. The percentage of liquid sulfur dioxid to be added to the mixture to be purified may be varied within fairly wide limits, and the desirable amount varies with the degree of contamination of the gasoline. A 80 single treatment is sufficient to recover substantial quantities of terpene products, but one or more additional treatments may be necessary for more complete recovery.

It should also be understood that it is not 85 essential that the gasoline should be freed entirely of its terpene compounds in order to fit the gasoline for re-use. The degree to which the sulfur dioxid is cooled is not vital, so long as it is cooled sufficiently low to liquefy 90 it.

Within the term "terpene products," specified in the claims, I mean to include hydrocarbon soluble components of wood other than rosin, as for example, terpenes, terpene alcohols, etc.

95 Where in the claims I specify a gasoline, I mean to include any equivalent low boiling hydrocarbon or mixture of hydrocarbons, such as benzine, naphtha or the like, which 100 may be used in the rosin-extracting process, and which is only slightly soluble in liquid sulfur dioxide.

Having now fully described my invention, what I claim and desire to protect by Letters 105 Patent is:

1. The process of effecting a substantial separation of terpene products from a mixture thereof with a gasoline which comprises treating the mixture with liquid sulfur dioxid 110

to dissolve out terpene products and separating therefrom the lighter gasoline-containing layer.

2. The process of effecting a substantial separation of terpene products from a mixture thereof with a gasoline which comprises treating the mixture with liquid sulfur dioxid to dissolve out terpene products and form a lighter layer comprising partly purified gasoline and a heavier layer comprising terpene products in solution in liquid sulfur dioxid, and retreating the lighter layer with liquid sulfur dioxid as before to effect separation

from the gasoline of additional terpene products.

3. The process of effecting a substantial separation of terpene products from a mixture thereof with a hydrocarbon distillate which comprises treating the mixture with liquid sulphur dioxid to dissolve out terpene products and separating therefrom the lighter hydrocarbon compound layer.

In testimony of which invention, I have hereunto set my hand, at Baltimore, on this 25th day of May, 1927.

EBENEZER EMMET REID.
